Primary Examiner — Cynthia R Underwood(74) *Attorney, Agent, or Firm* — Paratus Law Group,
PLLC(57) **CLAIM**

The ornamental design for a string adjuster, as shown and described.

DESCRIPTION

FIG. 1 is a front, top, and right perspective view of a string adjuster, showing the claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 shown in FIG. 2; and,

FIG. 9 is a back, top, and left perspective view thereof.

The long dash short dash broken lines and arrows shown in FIG. 2 are used to identify the cross-sectional view and form no part of the claimed design.
